(57) CLAIM

The ornamental design for footwear as shown and described.

DESCRIPTION

The patent or application file contains at least one drawing executed in color. Copies of this patent or patent application publication with color drawing(s) will be provided by the Office upon request and payment of the necessary fee.

FIG. 1 is a front left perspective view of the footwear in color;

FIG. 2 is a front view of the footwear in color;

FIG. 3 is back view of the footwear in color;

FIG. 4 is a right-side view of the footwear in color;

FIG. 5 is a left-side view of the footwear in color;

FIG. 6 is a top view of the footwear in color;

FIG. 7 is a bottom view of the footwear in color;

FIG. 8 is a front left perspective view of the footwear in grayscale;

FIG. 9 is a front view of the footwear in grayscale;

FIG. 10 is back view of the footwear in grayscale;

FIG. 11 is a right-side view of the footwear in grayscale;

FIG. 12 is a left-side view of the footwear in grayscale;

FIG. 13 is a top view of the footwear in grayscale; and,

FIG. 14 is a bottom view of the footwear in grayscale.
